(57) **CLAIM**

I claim the ornamental design for a double fishing pole holder with carrying handle, as shown and described.

DESCRIPTION

FIG. 1 is a perspective view of a double fishing pole holder with carrying handle showing my new design;

FIG. 2 is a front elevational view thereof, the rear elevational view being identical thereto;

FIG. 3 is a right side elevational view thereof showing the double fishing pole holder with carrying handle in use, the left side elevational view being a mirror image thereof; the broken lines depict environmental structure for illustrative purposes only and form no part of the claimed design;

FIG. 4 is a top plan view thereof; and,

FIG. 5 is a bottom plan view thereof.
